UNITED STATES PATENT OFFICE

133,434

DESIGN FOR A MERCHANTISING DISPLAY TABLE

Bernard A. Graham, Chicago, Ill., assignor to Chicago Flexible Shaft Company, Chicago, Ill.,
a corporation of Illinois

Application November 21, 1941, Serial No. 104,233

Term of patent 14 years

To all whom it may concern:

Be it known that I, Bernard A. Graham, a citizen of the United States, residing at Chicago, in the county of Cook and State of Illinois, have invented a new, original, and ornamental Design for a Merchandising Display Table, of which the following is a specification, reference being had to the accompanying drawing, forming part thereof.

In the drawing:

I claim:

The ornamental design for a merchandising display table, substantially as shown.

BERNARD A. GRAHAM.
